UNITED STATES PATENT OFFICE

99,431

DESIGN FOR A FLOOR RADIATOR

Michael Coyne, Washington, D. C.

Application September 10, 1935, Serial No. 58,505

Term of patent 14 years

To all whom it may concern:

Be it known that I, Michael Coyne, a citizen of the United States of America, residing at the city of Washington, District of Columbia, have invented a new, original, and ornamental Design for a Floor Radiator, of which the following is a specification, reference being had to the accompanying drawing forming a part thereof.

Figure 1 is a perspective view of the floor radiator showing my new design.

Figure 2 is a side view thereof.

I claim:

The ornamental design for a floor radiator as shown.

MICHAEL COYNE.
